UNITED STATES PATENT OFFICE.

WYNANT TASTENHOYE, OF MENIN, BELGIUM.

VEHICLE JACK.

Application filed December 4, 1923. Serial No. 678,487.

To all whom it may concern:

Be it known that I, WYNANT TASTENHOYE, a citizen of the Kingdom of Belgium, residing at 12 Rue d'Ypres, in Menin, Kingdom of Belgium, have invented certain new and useful Improvements in Vehicle Jacks; and I do hereby declare the following to be a full, clear, and exact description of the invention, such as will enable others skilled 5 in the art to which it appertains to make and use the same, reference being had to the accompanying drawings, and to the letters and figures of reference marked thereon, which form a part of this specification. 10 15 This invention relates to liquid-pressure hoisting-attachments to motor-cars and other vehicles, the object in view being to produce a simple and efficient device by which the pressure produced by a pump- 20 plunger is distributed to one of several jacks fastened to the vehicle and the hoisting-piston of which is controlled by a special coil-spring which, being stretched during the downwards stroke of the jack-piston, tends 25 to draw said piston back into its cylinder and to force the pressure-liquid back into the reservoir through the same distributing and return device.

In fact, a number of liquid-pressure hoisting devices fixed to the underframe of motor-cars have been proposed heretofore, but they all presented the twofold inconvenient that, first, the distribution of pressure liquid from the pump to any desired 30 one of the jacks, and the return and recuperation of said liquid after release of the pressure, required a complicated and expensive construction of valves or cocks, the operation and control of which were 35 also intricate; secondly, that the spring necessary for returning the jack-piston did 40 take a comparatively large room within the jack cylinder, thus reducing the stroke of the piston, unless telescoping systems were 45 resorted to, which however did only ensure a sufficient strength when considerably increasing the weight of the jack.

This present invention avoids both defects, on one part by connecting each of the 50 jacks by a separate conduit-pipe, with one and the same liquid-pressure distribution and return cock of special construction, directly connected and fastened to the compression chamber of the pump and, on the 55 other part, by using for returning the jack-piston, a tension coil-spring fastened with

its lower end at the foot of the jack-piston and with its upper end in the upper part of the jack-cylinder within which it is guided and located in a separate annular chamber 60 formed by a double wall of said cylinder.

By this arrangement, one and the same cock-key controls, according to the position it is rotated to, either the pressure or the release in or from any one of the jacks, as 65 required, and moreover, the complete length of the jack-piston can be used for hoisting the car, whilst the complete return of the piston into the cylinder of the jack, forcing the liquid back into the reservoir, takes 70 place under the tensile strength of the spring when the cock-key has been rotated to the position corresponding to pressure-release.

Other systems have been known for obtaining the same results but they all require the handling of several or separately with the fluid reservoir. The present invention uses only one special cock which, by the operation of only one cock-plug producing 75 80 either the communication between the pump and every one of the jacks individually or the communication between every jack individually and the fluid reservoir.

My invention comprises various details of 85 construction, combinations and arrangements of parts which will be hereinafter fully described, and shown in the accompanying drawings and then specifically defined in the appended claims. 90

In the drawings in which the invention is illustrated in a four-jacks application to a motor-car,

Figs. 1 and 2 are general views of the complete arrangement, Fig. 1 being a side 95 elevation and Fig. 2 a rear elevation.

Fig. 3 is an axial vertical section of one of the jacks when closed, i. e. in inoperative position.

Fig. 4 is a vertical section on line V—U 100 Fig. 1, showing the reservoir containing the liquid, the pressure-pump and the special distribution and return-valve or cock.

Fig. 5 is a corresponding section taken on line W—X of Fig. 4 and 105

Fig. 6 is a plane-section on line Y—Z of Fig. 4.

Referring to the drawings, Figs. 1 and 2, the attachment is composed, as well known in the art, of a reservoir A, that can be fastened on the foot-board or at any suitable place; said reservoir is filled with a suit-

able liquid or fluid, preferably non-freezing-oil, and encloses an ordinary pressure-pump of any well known construction such as B, preferably having a horizontal plunger 5 such as B¹, driven by a lever such as L, for compressing the liquid from reservoir A into the pressure-chamber B² upon which is directly fastened and connected the improved distribution and return device C, 10 that opens or closes as desired, the communication with any one of the pipes D, each of which communicates with one of the pressure-jacks E.

The distribution and return-device C is 15 a sort of multi-way-cock. The shell C¹ of said cock presents four ways and nozzles C²—C²—C²—C², each of which is connected to an exterior pipe D leading to one of the jacks E. Said four ways C²—C² are 20 bored in one and the same horizontal level and open internally in the front half of the shell, leaving between each other sufficient width of solid metal for making a tight fit against the opening of a passage C⁴ bored 25 radially in the plug C³ and having the same cross-section as the ways C², in such a manner that said opening C⁴ can be alternately closed by the solid wall of the shell or brought into communication with one of the 30 ways C²—C², according to the position to which said plug has been rotated.

Said passage C⁴ is vertically protracted downwards in the axis of rotation of the plug and communicates directly and permanently, with the pressure-chamber B² of 35 pump B.

Same cock-shell C¹ is moreover provided, at a horizontal level lower than the level 40 of the ways C²—C², with an annular groove that communicates with a canal C⁶ and a return conduit to the reservoir A. On its side diametrically opposed to the peripheral opening of passage C⁴, the plug C³ is provided with a vertical groove C⁸, the width 45 of which is somewhat larger than the diameter of the ways C²—C² whilst its length is somewhat greater than the distance between the highest point of ways C² and the lower side of groove C⁸.

Owing to this construction, a part-rotation 50 of plug C³, brings passage C⁴ in alignment with one of the ways C², and since the direct communication with the pressure-chamber B² of pump B, is always free at 55 its lower end, it opens at its upper end the connection with the pipe D and jack E corresponding to said way C². After a sufficient pressure in the desired jack E having been obtained by the action of the 60 pump-plunger B¹, the opening of passage C⁴ is brought, by rotating the plug C³, either in front of a solid part of the shell, or in front of another way C², the pressure being maintained in the operated jack. When 65 the passage C⁴ has been brought in alignment

with another way C², pressure may be applied in the above manner, to the jack corresponding with same. When, however, the rotation of plug C³ is continued until the vertical groove C⁸ comes in alignment with the way C² corresponding to the laden jack, same opens the communication between said way C², annular groove C⁵, hole C⁶ and return conduit C⁷, thus allowing the liquid in the laden jack E to be forced 70 back into reservoir A, under the return-stroke of the jack-piston E¹.

But this return stroke of the jack-piston E¹, although being produced in its first 75 part by the mere weight of the car, so long as same bears upon the jack, would not continue when the four wheels rest on the ground and said piston has no more load to bear. It is thus necessary for the continuation of said stroke to be produced by a 80 spring, returning the jack-piston E¹ into the jack-body with a sufficient excess of strength 85 for forcing the liquid back to the reservoir.

On the other hand, it is necessary that 90 said spring be arranged so as to find its 95 housing within the jack-cylinder, without interfering neither with the length of the piston-stroke, which latter must be sufficient for hoisting the car at the required level, regardless of the possible unevenness of the soil, nor with the tightness of the 100 jack-piston.

In accordance to the present invention, 105 these results are obtained in forming the jack-body of a double-wall cylinder such as E², the head E⁵ of which is connected through a bored conduit with the corresponding pressure pipe D. In the annular chamber between the double-wall is fitted 110 the coil-spring E³, fastened at its upper end by two screws E⁴ passing through the outer-wall of the jack-body and between the spring-coils. In the cylindrical chamber formed by the internal wall, fits tightly a 115 jack-piston E¹ provided at its upper end with a leather or other suitable packing such as E⁸ and at its lower end with a tread-shoe E⁷. Immediately above said shoe E⁷, the piston is formed with an annular shoulder E⁶ of suitable height and width 120 for allowing two coils of the spring E³ to be screwed on same, the mere retraction or contraction of the spring ensuring a strong grip which tightens more and more when piston E¹ is forced down by the liquid-pressure and stretches out spring E³. In 125 order to avoid said pressure forcing the jack piston E¹ completely out of cylinder E², the internal wall of same may be provided at the critical point of the downward stroke, with an upwardly turned hole E⁹, through which the pressure liquid will flow out into the annular housing for spring E³; this will cause an instantaneous release of the resistance in the pump and warn the operator to 130

cease his pumping. This small quantity of oil will not be lost, since it will lubricate the housing of the spring.

When the pressure is relieved by operating the distribution and return cock as above described, the jack-piston will rise, and the car descend, first under the double effect of the car-weight and of the spring tension, and later under the influence of 10 spring E³ alone, until said spring E³ and the piston E¹ have completed reintegrated their respective housing within the jack-cylinder E². It will be readily observed that inversely to what occurs in any other system known 15 heretofore, the housing of spring E³ being separated from the housing of jack-piston E¹, said jack-piston is free to work with its whole length, which cannot be the case when using springs that are compressed 20 within the jack-cylinder during the downward stroke of the piston for returning same later by their expansion. Moreover it is not necessary to resort to telescoping arrangements which are always complicated, 25 weak, exposed to leakage, and heavy.

Another advantage of this jack arrangement is that the double-wall of the cylinder are reinforced by the coils of the spring and can thus be made comparatively thin 30 without danger of deformation or undue stress at the points where they are pressed in the clips H, fastening the jacks to the axles or other parts of the underframe.

It will be seen that the return conduit C⁷, 35 protracting downwards in the reservoir, is continued upwards to the top of the shell C¹ where it is obturated by a screw plug such as E¹⁰ for allowing to refill the reservoir A, when necessary; an air-hole in said plug 40 excludes any excess of pressure in reservoir A that would hinder the readmittance of liquid in same.

Moreover, the plug-key E¹¹ is shaped to 45 form an index-pawl registering with the position-marks on the upper part of the cock-shell.

Although the illustrated form of execution has been shown and described as embodied in an arrangement with four jacks, 50 same could of course apply to an attachment with any other number of jacks, every jack being of the specified construction and the number of ways in the cock-shell and of pressure distributing-pipes always corresponding to the number of jacks.

It should be understood that the arrangement and construction of pump and pipes, the method of securing the pump, pipes and jacks on the car, and their respective position 55 are not included within the scope of the

present patent, which is intended to cover only the features specified in the appended claims.

What I claim as new is:

1. Lifting devices for a vehicle comprising a plurality of fluid pressure jacks applicable to the vehicle, a fluid pressure pump and a reservoir, connections between the jacks and the fluid pump, a distributing device between the pump and said connections for delivering fluid to the jacks alternately, and means in said distributing device for returning the fluid from the jacks to the reservoir. 65 70

2. Lifting devices according to claim 1, 75 in which the fluid distributing device comprises a shell having one or more ports for conveying liquid to conduits connected to the jacks, and a single port leading to the fluid containing reservoir, said distributing device comprising a plug having a port which, by rotation of the plug, can be brought alternately into coincidence with each and all of the distributing ports, and said plug having also a groove which, upon further rotation of the plug can be brought alternately into coincidence with said distributing ports to convey liquid from the jacks back to the reservoir through the aforesaid single port. 80 85 90

3. Fluid-hoisting attachments for vehicles including a fluid pressure jack comprising, a head having a fluid passage therein, a cylinder having double concentrically spaced walls extending from said head, a piston in said cylinder having a plunger and lifting member on its outer end, and a spring between the spaced walls of the cylinder connected at its innermost end with the cylinder and at its other end with the piston plunger so as to normally maintain the piston in its innermost position. 95 100

4. A fluid pressure jack comprising a piston and plunger member having a lifting member on its outer end, a cylinder for said piston having at one end a head having a fluid passage therein and adjacent to its other end an aperture for limiting the extreme movement of the piston therein and providing a passage way for the fluid whereby the fluid may be emitted as a lubricant on the outside of the cylinder, a spaced concentric wall surrounding said cylinder, and a spring within said space surrounding the cylinder and connected at 110 115 its ends with the jack members.

In testimony that I claim the foregoing as my invention, I have signed my name.

WYNANT TASTENHOYE.
